DRAPEY SUPPORTING MEANS

Philip Rosenzweig, Detroit, Mich.

Application March 14, 1955, Serial No. 493,940

2 Claims. (Cl. 16—87.4)

This application relates to drapery supports and particularly relates to a novel form of slider or carrier for a slotted or traverse track designed to receive and to support a drape supporting means in proper manner.

An object of the present invention is to provide a socketed slider whose socket is oblique and in a vertical plane, with the lower part of the socket behind the upper part, and the upper part directly below the track.

Such device is shown in the appended drawing which shows a slotted track in transverse section, with a slider, a drape supporting means, and a fragment of drape all in place and with the slider and the drape supporting means being in the preferred form.

The drawing shows a rearwardly slotted or traverse track 10 in which may slide horizontally a plurality of sliders or carriers 12, each having a body portion 13, a depending member 14 and a socket means 30 whose socket 16 closely fits and receives the hook 18 of a drape supporting means 19 which includes a drape engaging part 20 which engages the upper edge portion 22 of a drape whose lower part is referenced 24.

While the drape engaging part 20 of the drape supporting means may comprise one or more fingers it is understood that for the purposes of this application the drape

2

engaging part is considered simply as a means for rigidifying the upper edge of the drape and for connecting it to the hook proper 18 whereby the drape as a whole may be supported in the slider 12 and thus in the track 10.

- 5 For purposes of illustration I have shown a drape engaging part of three finger form as shown in my prior application Serial No. 473,079 dated December 6, 1954 wherein the three fingers engage within pleats of a drape to stiffen the upper part of the drape and to support it.
- 10 The drawing shows the socket 16 in a vertical plane and so obliqued that its upper end 27 is forward of its lower end 28 and yet is not forward of track 10 or body 13, but is directly below these parts, to prevent undesirable tilting and swinging of the hook not only forward but also sidewise.

Now having described an embodiment of the invention, reference should be had to the claims which follow:

What is claimed is:

1. A slider for movement in a track member, said 20 slider comprising a body portion slidably movable in said track member, a vertical member depending from said body portion and supporting an oblique socket means having a socket lying in a vertical plane transverse to the direction of movement of the slider with the upper end of 25 the socket forward of its lower end.
2. A slider as defined in claim 1 with the upper end of the socket lying directly below the body portion.
